ALBERT PONCET, OF CHAMPIER, FRANCE

AUTOMATIC SHUTTLE CHANGING MECHANISM FOR A LOOM WEAVING WITH ONE OR SEVERAL SHUTTLES

Application filed January 7, 1932; Serial No. 585,301, and in France January 14, 1931.

My invention relates to an automatic shuttle-changing mechanism for a loom weaving with one or several shuttles.

This mechanism operates with a weft 5 thread-feeler and, when the weft is exhausted it stops the loom and starts a shuttle-changing gear which, when its operation is perfected, re-starts the loom.

In this mechanism, the weft-feeler operates 10 a selecting gear which stops the loom not at once but at the next passage of the exhausted shuttle in the shuttle-changing box. As it is well known, the weft feelers operate before the complete exhaustion of the weft and 15 there is no objection in the shuttle being passed twice more through the web.

This mechanism is besides intended to be 20 easily applied to existing looms void of shuttle-changing gear. It is devised to be placed laterally of the loom and with a minimum 25 adaptation of the same.

In the annexed drawings:

Fig. 1 is a profile view of the mechanism when no shuttle has to be changed, the front 25 frame being supposedly removed.

Fig. 2 is a plan view of the same, the parts inferior to line X—X of Fig. 1 being not illustrated for the sake of clearness.

Fig. 3 is a section of Fig. 1 on line X—X 30 of the same.

Fig. 4 is a vertical cross-section of Fig. 1 on line Y—Y of the same.

Fig. 5 is a front view of the shuttle stock.

Fig. 6 is a cross-section of the same on line 35 VI—VI of Fig. 5.

Fig. 7 is a detailed side view of the selecting gear, with parts in section.

Fig. 8 is a front view of the same.

Fig. 9 is a plan view of the same. 40 Figs. 10 and 11 are side views similar to Fig. 1, but at two different positions during the operation of the shuttle-changing gear.

Figs. 12 to 14 are diagrams showing the cams and their relative position.

The mechanism illustrated is supposed to 45 be adapted to a loom of known type, having two shuttles. This loom is not illustrated and only the slay has been diagrammatically represented with the weft feeler.

All the parts of the mechanism are ar-

ranged laterally of the loom on the side opposed to the shuttle boxes. They are supported by the left frame 32 of the loom and an additional frame 33 parallel to frame 32.

The driving gear of the loom is modified, 55 the normal clutch being replaced by a double clutch of any description. In the example illustrated, this clutch is of the cork type. It comprises two opposed plates 2 and 4, fixed on a common hub 3. Plate 2 is loose on the 60 driving shaft 1 of the loom and its rim forms a pulley 5 for the driving belt not shown. Plate 4 is loose on a hub 6 keyed on shaft 1, this hub being provided with a ball thrust-bearing against which abuts a heavy helico- 65 dal spring 8. The latter thus presses plate 2 against a brake pulley 9 loose on shaft 1. A gear wheel 10, also loose on shaft 1, is keyed with pulley 9.

Shaft 1 also loosely supports a third plate 70 11, the hub of which is provided with a worm screw 12 cooperating with a worm wheel 14 keyed at the upper end of a vertical shaft 15. The lower end of the latter is provided with a worm 16 cooperating with a worm wheel 17 75 keyed on a shaft 18 supported by an appropriate bearing fixed onto frame 33.

Shaft 18 is provided with two cams 19 and 20, which are figured side by side to an enlarged scale in Fig. 12, their mutual relation 80 being thus clear.

The shaft 22, which is located below shaft 1 is the picking shaft of the loom, this shaft being rotated at half the speed of shaft 1 through gears 10 and 21 as usual. Shaft 22 85 is provided with a disk 23 having a notch 24. This disk is clearly shown in Figs. 13 and 14, which also demonstrates its relation with respect to the slay and to its cooperating tooth 34a which will be further described below. 90 As shown, shafts 18 and 22 are co-axial, and at an axial distance from each other.

When spring 8 is free from any control, it 95 clutches plate 2 with brake pulley 9. The latter and pinion 10 are thus connected with shaft 1 which is positively driven. The loom is operated. Plate 11 is de-clutched and remains at standstill. Hub 3 is provided with a circular groove 3a which receives the bifurcated ends of a controlling fork 25 pivoted 100

on a fixed shaft 26 provided with a controlling lever 27. The latter is connected through a vertical rod 28, with the end of one arm 29 of an horizontal double-armed lever 29—30 loose on a journal 31 fixed to frame 33.

A lever 114, pivoted to frame 33 is situated upon the free end of arm 30 of lever 29—30. The end of lever 114 is shaped so as to form an oblique portion which may be operated by the ordinary hand de-clutching lever (not illustrated).

A second double-armed lever 34, 35 is the essential part of this invention since it controls the stoppage of the loom and the operation of the shuttle-changing mechanism and afterwards re-starts the loom when the latter is perfected.

This lever is formed of two arms 34, 35 located in the same horizontal plane but in two different vertical planes as shown in Fig. 3. These arms have their hubs 36 keyed on a common shaft 37 which is rotatably supported by frames 32, 33. Arm 35 is situated near frame 33 and it is directed toward the front of the loom. Articulated at its end is an upwardly directed vertical rod 38 guided in guiding rings 39. Arm 34 is loaded by a heavy helical spring 42 having its lower end attached to the frame (Fig. 1). This arm has an arcuate portion 40 over a bifurcated cam 47, 48 keyed on a shaft 43. Keyed on said shaft 43, in front of cams 19, 20 are on the one hand a cam 45 provided with a notch 46, and adapted to cooperate with a roller, 50, supported by arm 29; and on the other hand an arm 49 provided with a front nose cooperating with notch 19a of cam 19.

Shaft 43 is provided with a third cam 51 which cooperates with the free end 52 of a semicircular jaw 53 pivoted at 54, this jaw operating as a brake for pulley 9. Jaw 53 is loaded by a spring 56, the latter being less strong than spring 42.

The selector device is internally supported by frame 33 high enough to permit its cooperation with the slay at the forward position thereof (Fig. 1). This device comprises a carriage 58 adapted to slide on an horizontal plate 59 supported by frame 33 and traversing the same (Fig. 9). Plate 59 is provided with a guiding groove 59a which cooperates with an appropriate depending projection of carriage 58.

Carriage 58 is provided with two parallel transversal grooves in its lower face, and these grooves cooperate with two slides A and B which will be hereinafter referred to as the selectors. The length of these selectors is greater than the width of carriage 58. They normally project from the front edge of the latter (Fig. 9) while being flush with the rear end of the same. Two holes 58b and 58c are provided through carriage 58, so as to cross the grooves wherein the selectors are housed. Each one of the latter is also provided with a

hole *a* or *b* located so as to be normally in front of holes 58b or 58c respectively, and to cooperate with the same and also with hole 59b of plate 59 when this selector has been brought over rod 38 and in front of a lever 105 which is intended to push the selector as it will be hereinafter explained. The selectors are adjusted within their grooves with a material friction in such a way that they remain at any position notwithstanding the loom vibrations. This friction may also be obtained through spring brakes or the like. The holes *a*, *b*, 58b, 58c and 59b are larger in section than rod 38, the latter thus operating with a substantial clearance.

Carriage 58 is also provided with an upward projection 60 which is operated by a forked member 61 keyed on the upper end of a vertical spindle 62; the lower end 63 of the same pivots in a step-bearing 64 fixed to the frame. A lever 65 (Fig. 3) is also keyed on spindle 62 in the lower portion thereof. Articulated on lever 65 is a rod 66 which is also pivoted on a vertical lever 68 (Fig. 1) keyed on the end of a shaft which is driven from one end of the loom to the other end. The other end of this shaft is provided with the well-known square adapted to receive the action of the cam controlling the shuttle boxes. It will be easily grasped that the operation of this square causes shaft 67 to rotate correspondingly, lever 68 being moved through the same angle, whereby spindle 62 is rotated through rod 66.

A two-armed lever 71—72 is pivoted on a shaft 73 supported by frames 32, 33 (Fig. 1). This lever is vertical and its lower arm 72 is provided with a slit whereby it is connected with the rear end of rod 66; the upper arm 71 is pivoted to an horizontal lever 74, the other end of which is provided with an elongated arcuate opening 77 adapted to receive a pin 76 which projects from a lever 78 pivoted at 85. The latter is intended to bring a shuttle from the shuttle stocks 101 and 102. For this purpose, the upper end of said lever is provided with a plate 100 adapted to receive a fresh shuttle. This plate could also be independent from lever 78 and arranged slideable in appropriate oscillatable guiding members, which would be controlled by lever 78.

Lever 78 is provided with projecting pins 79, 80, suitably located. Pin 79 cooperates with the forked end 87 of an oblique lever 86 articulated at the free end of a lever 88 keyed on shaft 43. Pin 80 is designed to maintain lever 78 at any one of two positions corresponding to the two shuttle stocks 101 and 102 (Figs. 1 and 2). A catch 106, supported by a fixed shaft, is provided with two successive notches 107, 108, adapted to cooperate with pin 80 at the two respective positions of lever 78 (since the mechanism comprises two shuttle stocks).

A lever 89, keyed on a fixed shaft 91, is

adapted to permanently contact cam 20 through a roller arranged at its free end. There is also keyed on the same shaft: a lever 90 to which is articulated a rod 92 connected 5 to the arm 93 of a bell-cranned lever 95 pivoted at 94 on the slay 115; a lever 90a parallel to lever 90 and in the same horizontal plane, but in a different vertical plane in such a way that a pin 55 fixed near the free end 10 thereof can be situated over the rear end 116 of a lever 118 oscillatably supported by a fixed shaft 119, the front end of said lever lying under the lower end of a rod 120 laterally supported by lever 78. Rod 120 is arranged 15 slidably on lever 78 and it is adapted to control through its upper end, a finger 121 (Figs. 5 and 6) arranged on the left side of plate 100 and in a vertical plane corresponding to two rods 130 and 131 depending along 20 the left walls of shuttle stocks 101 and 102 (Fig. 6). Finger 121 is pivoted on the upper end of lever 78 and it is also pivotally connected with rod 120; its free end is brought under one of rods 130, 131 according 25 to the position of lever 78 as it will be herein-after explained.

The shuttle stocks are, as a whole, fixed over the breast beam of the loom, at the opposed side thereof with respect to the shuttle boxes, 30 over the fresh-shuttle receiving plate 100 and in front of the lateral opening provided in the slay and closed by the cranked lever 95.

Each shuttle stock is divided by two partitions: a transverse one 129 and a longitudinal one 129a. There is thus formed the stock proper 101 or 102 and a housing for the shuttle distributing gear. The latter comprises the depending rod 130 or 131 which is pivotally attached to an arm 132 integral with 35 a lever 133 oscillatable on a fixed shaft. Attached to the free ends of lever 133 are two rods 134 and 135, unequal in length. The latter are respectively connected with two levers 136 which drive rollers 137 having a peripheral V-shaped notch 138. These notched rollers are located at the ends of the stock, partitions 129 and 129a being apertured to 40 accommodate said rollers which are appropriately devised so as to be freely rotatable on their respective shafts. Lever 133 is loaded by a spring 139, whereby its lower end abuts against the left wall of the shuttle stock. Rods 134 and 135 thus maintain rollers 137 at the position shown Fig. 5, the lower shuttle 45 of the stack being supported by its ends.

The cranked lever 95 is arranged on the slay in such a way that its front arm closes the front opening thereof, as it is well-known in the art. For this purpose, a spring 89a 50 is provided to press lever 89 against cam 20. The slay is also provided with a fixed longitudinal shaft 99 rotatably supporting two independent vertical forks 98, each having a tail 97 which is passed through an appropriate vertical slit provided in the front arm of 55

lever 95, this slit being closed by a pin 96. Forks 98 are disposed in such a way that their lower ends are in cooperative position with the working shuttle when the latter has been stopped by the buffers.

There is also provided a part which is only controlled by the weft feeler when the pirn is nearly exhausted, said part in turn operating the selector corresponding to the working shuttle. This part comprises two levers 104 and 105 keyed by screws at a predetermined interval on a common horizontal shaft 103 rotatably supported by the frames. The position of this gearing is dependent of the type of weft-feeler employed. In the case illustrated, the weft feeler is a vertical rod T having an horizontal nose t projecting towards the front end of the loom (Fig. 1). This rod T is sunk into the shuttle by any appropriate means, its lower end contacting the pirn C.

Lever 104 is curved at right angle; its end projects towards the slay and is at such a height that it may cooperate with nose t when the pirn is exhausted, as shown in dotted lines Fig. 7.

Lever 105 is arranged to vertically depend exactly in front of selector A when shuttle box No. 1 operates (Figs. 1, 2 and 7, 11) and of selector B when shuttle box No. 2 operates.

A cranked lever 110 is located between rods 38 and 62. This lever is pivoted on a fixed shaft and it is loaded by a spring 140 which presses it against a stop 141. The lower end of lever 110 is bifurcated and accommodates rod 38. The latter is provided with two rings 111 and 112, fixed by screws at predetermined places and adapted to respectively cooperate with the lower arm of lever 110 and with catch 106 as it will be described.

Fig. 1 shows the mechanism during the normal operation of the loom. Plate 11 is de-clutched and pulley 9 is clutched with plate 2 through hub 6 which drives shaft 1. Shaft 22 is also rotated and the loom operates as long as it is not willingly stopped and as long as there remains weft on the pirns.

To stop the loom, the operator acts on the hand de-clutching lever which lowers lever 114 of a pre-determined amount and thus oscillates lever 29, 30 for exactly the angle required to move lever 25 and to impart to hub 3 exactly the axial displacement whereby plates 2 and 4 are de-clutched at the same time.

When the loom is clutched, Fig. 1, the shuttle having weft in sufficient quantity, as shown in dotted lines in Fig. 1 and in full lines in Fig. 7, nose t is always over the end of lever 104 as clearly illustrated in full lines, Fig. 7.

When the weft is nearly exhausted, as shown in dotted lines, Fig. 7, the weft feeler is at its lowermost position and nose t abuts the end of lever 104, the shaft 103 of which

is rotated in proportion; lever 105 is also operated and it pushes selector A for the same length. The motion of the latter is so calculated that hole *a* is brought exactly coaxial with holes 58*b* of plate 59 and 58*b* of carriage 58.

Selector A remains at this position, but levers 105 and 104 return to their normal position when the slay returns backward. Lever 34—35 cannot then oscillate since tooth 34*a* is not over notch 24 of disk 23. The latter is adjusted on the picking shaft 22 in such a way that notch 24 is at the upper part of disk 23 (i. e. under tooth 34*a*) only when the slay is returning backward, slightly before the right-to-left stroke of the operating shuttle (Fig. 14). Thus, notch 24 and tooth 34*a* are in cooperative relation just before the operation of the weft feeler, but they are out of cooperative relation when the latter operates.

The loom is consequently not stopped and the shuttle is returned to the right. But at the next stroke (from right to left) of the same shuttle, tooth 34*a* passes over notch 24 and lever 34—35 can oscillate under the action of spring 42, since the upper end of rod 38 finds its way through the superposed holes 59*b*, *a* and 58*b*.

This oscillation of lever 34, 35 has the following consequences:

Firstly, pulley 9 is braked and picking shaft 22 is stopped; pulley 5 is clutched (through plate 4) with plate 11 and thus shaft 18 with cams 19, 20 is rotated. This shaft controls the shuttle changing operation which comprises: rejecting the exhausted shuttle, extracting a fresh shuttle from the shuttle stock, inserting the same into the slay, de-clutching plate 11, releasing pulley 9 and clutching pulley 9 to re-start the loom.

It will be hereinafter supposed that box No. 1 is in operation; consequently shaft 67 (which is controlled by the box selecting gear) is at its first position as well as lever 68, as shown in Fig. 1.

1. Lever 71, 72 is oblique and has brought lever 74 into such a position that the end of slit 77 has pulled lever 78 through pin 76, pin 80 having passed over notch 107 of catch 106, whereby lever 78 is maintained at its first position, plate 100 being exactly under shuttle stock 101 in which are stacked the shuttles No. 1.

2. The pre-determined rotation of fork 61 under the action of rod 66 through lever 65 and spindle 62 is so calculated that the resulting motion of carriage 58 brings selector A in front of lever 105 as shown in full lines, Figs. 7 to 9.

Arm 34 also acts on the end 47 of cam 47—48 and thus rotates the latter together with cams 45 and 51 and lever 49, through shaft 43. The arrow, Fig. 10, shows the direction of this rotation. As a result of such a rotation,

arm 29 of lever 29—30 is moved upwardly through roller 50 and cam 45; and also cam 51 frees the end 52 of brake 53 and the latter, under the action of spring 56, stops pulley 9. Also rod 28 is pushed upwardly and fork 25 moves hub 3 against the action of spring 8, whereby plate 2 is de-clutched from pulley 9 and plate 4 is clutched with plate 11. The loom is stopped almost instantaneously, the slay being just at its rearmost position when the standstill is obtained.

Owing to the partial rotation of shaft 43, the end of arm 49 escapes from notch 19*a* of cam 19. Also lever 88 is rotated and operates lever 86 the forked end 87 of which is thus brought near pin 79 of lever 78, as shown, Fig. 10.

Plate 11 being clutched with pulley 5, shaft 18 is rotated at a very low speed through gears 12, 14, 16 and 17. The speed of said shaft may be, for instance, the twelfth of that of shaft 1.

During this rotation, cam 20 drives the roller of lever 89 keyed on shaft 91; levers 90 and 90*a* are thus lowered; lever 90 pulls rod 92 which operates lever 95; the latter opens the lateral opening of the slay (Fig. 11) and drives forks 98 through tails 95. The shuttle N is thus rejected from the slay and is received into an appropriate receiver.

Lever 90*a*, through pin 55, operates the tail 116 of lever 118 and the latter operates rod 120 whereby finger 121 is moved upwardly. Finger 121, in turn, operates rod 130 of shuttle stock 101. Lever 133 is thus rotated for a determined angle and it drives rods 134, 135 sufficiently to free the first shuttle which was supported in the notches 138 of rollers 137 and also to retain the further shuttles. When finger 121 is restored to its normal position, rollers 137 receive into notches 138 the ends of the last shuttle of the stock, as it will be easily grasped from Fig. 5.

The first shuttle N 101 falls on plate 100. The action of cam 19 then begins. Arm 49 is rotated, whereby lever 88 drives lever 86 which in turn drives lever 78 for an angle calculated so that plate 100 penetrates into the slay as shown in Fig. 11.

Cam 20 then releases somewhat lever 89, whereby lever 95 is returned backward for a limited amount; shuttle N 101 is thus retained within the slay when plate 100 returns with lever 78.

A. When the peak of cam 19 is under the end of arm 49 (position of Fig. 11) the end 48 of cam 47—48 operates arm 34 of lever 34—35 which rotates clockwise. Arm 35 is thus lowered.

B. Owing to the lowering of arm 35, rod 38 is also lowered and clears the holes of the selecting gear. Ring 112 frees catch 106 and ring 111 strikes the forked end of lever 110 which in turn strikes by inertia selector A against the action of spring 140. Selector A

is restored to its former position (Figs. 1 and 7-9), whereby rod 38 is prevented from again rising. As a result thereof, lever 34-35 is locked at the position of Fig. 1.

5 Arm 49 then rotates anticlockwise under the action of spring 88a. Cams 45, 51 and 47-48 are thus progressively restored to their normal position of Fig. 1. When the end of arm 49 is in front of notch 19a, it falls thereto. Pin 50 also falls into the notch of cam 45, so that arm 29 of lever 29-30 is lowered, whereby plate 11 is de-clutched and pulley 9 is clutched. The loom is re-started.

10 The mechanism is thus ready for a further 15 operation when the weft of one or of the other shuttle will be exhausted, the shuttles being operative in regular or irregular succession according to the weave.

20 When the shuttle No. 2 operates, the shuttle box controlling gear drives shaft 67 and lever 68, the latter causing lever 71-72 to come into the position shown by the dashed lines in Fig. 1. Lever 74 is thus moved forward so that slit 77 permits pin 80 to move forward 25 (with respect to the loom). Plate 100 may thus be brought under shuttle stock 102.

25 On the other hand, rod 66 is pulled by lever 68 and spindle 62 is thus rotated, whereby carriage 58 is moved toward frame 33 so that 30 selector B will come in front of lever 105. It will thus be understood that when the weft will be exhausted in shuttle No. 2, the mechanism will operate as in the case above described, lever 78 being at its second position 35 (notch 108 of catch 106).

40 The mechanism may be used with looms having more than two shuttle boxes. Carriage 58 will be provided, for instance, with four selectors corresponding to four shuttle boxes; there would be used four shuttle stocks; catch 106 would be provided with four notches; slit 77 and lever 86 should be modified accordingly.

45 The shuttle-changing operation takes place not when the feeler has detected the weft exhaustion, but at the next passage of the exhausted shuttle. Since the weft feelers operate well before the complete exhaustion of the pirn, there is no objection to such an operation. Supposing that shuttle No. 2 is exhausted, it will nevertheless be returned into its box. If now shuttle 1 is to work, the mechanism will not operate since rod 38 will be under selector A which has not been pushed 50 by the weft feeler. The operation will take place only when shuttle No. 2 will again work, selector B having been pushed by the prior 55 action of the weft feeler.

60 In order to permit the shuttle to be well rejected from the slay, the ordinary shuttle buffer is to be supported by a cranked lever loaded by a spring so as to constantly contact the picking stick. Said lever is to be connected with rod 92 so that the buffer may clear the 65 shuttle during the rejection thereof.

One characteristic feature of this invention is that the parts are supported by a frame which can be joined to the frame of a standard loom on the side opposed to the shuttle boxes. Any kind of loom may be equipped with the 70 mechanism according to the invention.

The device permits to increase the speed of the looms weaving with several shuttles, thus increasing the output. The automatic operation permits of reducing the attention of the 75 operator who may simultaneously attend to a number of looms greater than without the invention.

I claim:

1. A shuttle-changing mechanism for 80 looms operating with several shuttles, comprising in combination a selector device adapted to be selectively actuated by the weft feeler of the loom when the pirn is exhausted said weft feeler being on the side of the loom 85 opposed to the shuttle boxes; means adapted to reject the exhausted shuttle from the slay; a plurality of shuttle stocks on the side of the loom opposed to the shuttle boxes; means 90 adapted to each one of said stocks to extract but one shuttle therefrom; a shuttle carrier adapted to selectively receive the fresh shuttle extracted from one of said stocks; means on said carrier, to selectively operate said 95 shuttle-extracting means; a control mechanism responsive to the shuttle box control, to drive said shuttle carrier in accordance therewith so that it cooperates with the stock corresponding to the shuttle in operation in the loom; means to move said shuttle carrier 100 so that it brings the fresh shuttle into the slay; a cam gearing adapted, when in operation, to drive all the aforesaid means in appropriate succession; a double clutch rotated by the general drive of the loom, said 105 double clutch being able to rotate either the loom proper or said cam gearing; braking means adapted to stop the loom when it is de-clutched from said double clutch; a cam gear continuously driven by the loom; and a 110 spring gear, retained simultaneously by said last-named cam gear and by said selector device, said spring gear being adapted, when freed, to actuate said double clutch so as to stop the loom and rotate said first-named cam gearing, the latter being arranged to reload said spring gear and also to restore said double clutch into its normal weaving position when the shuttle changing operation is 115 perfected; and said second-named cam gear being so adjusted with respect to the loom, that it frees said spring gear only during a short period of time and slightly before the 120 operation of the weft feeler.

2. In a shuttle-changing mechanism as 125 claimed in claim 1, means whereby the re-loading of the spring gear restores the selector device to its normal position.

3. In a shuttle-changing mechanism as 130 claimed in claim 1, a selector device com-

prising a movable carriage; slides on said carriage; means whereby each slide may be pushed by the weft feeler for an appropriate position of said carriage; means whereby a slide, when pushed, frees the spring gear which controls said mechanism; and means responsive to the shuttle box control, whereby said carriage is driven in such a way that each slide corresponds to a shuttle of the loom and is brought in operative relation with said weft feeler whenever said shuttle is in operation.

4. In a shuttle-changing mechanism as claimed in claim 1 means to extract the last shuttle of a shuttle stock wherein the shuttles are vertically stocked, comprising a pair of notched rollers, the notches of which are adapted to receive and retain the ends of the last shuttle; spring means to retain said rollers; and means to rotate the same in inverted direction whereby said last shuttle is lowered and dropped, while the preceding one is retained by the unnotched portion of said rollers.

5. In a shuttle-changing mechanism as claimed in claim 1, a shuttle carrier and control therefor comprising a lever pivoted to the frame on the loom; a shuttle supporting plate at the free end of said lever; a spring acting on said lever so as to drive it into its frontmost position, said plate then being under the frontmost shuttle stock, a driving means adapted to actuate said lever against the action of said spring, that is rearwardly with respect to the loom, the connection between said means and said lever being unidirectional, that is, permitting any rearward motion of said lever irrespective of the actual position of said means; and means driven by the cam gearing of said mechanism, said means being adapted to drive said lever rearwardly, whereby said shuttle-supporting plate brings the fresh shuttle into the slay.

6. A shuttle-changing mechanism as claimed in claim 1, wherein the cam gear continuously driven by the loom is a notched disk keyed on the picking shaft of said loom.

In testimony whereof I affix my signature.
ALBERT PONCET.
